[57] CLAIM

The ornamental design for a cartridge for a skin stapler cartridge, as shown and described.

DESCRIPTION

FIG. 1 is a perspective view of a cartridge for a skin stapler showing our new design, the broken line showing of a skin stapler being for illustrative purposes only, and forming no part of the claimed design;

FIG. 2 is a top plan view thereof;

FIG. 3 is a front elevational view thereof;

FIG. 4 is a right side elevational view thereof, the left side being a mirror image;

FIG. 5 is a rear elevational view thereof; and,

FIG. 6 is a bottom plan view thereof.
